SURGEON'S GOWN

Edwin Burnell Rhoads, Merion, Pa., assignor to Rhoads and Company, a partnership comprising Emma L. Rhoads, Merion, Jay R. Rhoads, Bryn Mawr, and Edwin Burnell Rhoads, Merion, Pa., engaged in business in Philadelphia, Pa.

Filed July 10, 1959, Ser. No. 56,738

Term of patent 3½ years

(Cl. D3—26)

FIG. 1 is a front view of the surgeon's gown, embodying my new design;

FIG. 2 is a side view of the surgeon's gown, and

FIG. 3 is a rear view of the surgeon's gown.

I claim:

An ornamental design for a surgeon's gown, as shown.
